UNITED STATES PATENT OFFICE

2,561,591

AIR DEFLECTOR

Oscar C. Palmer, Phoenix, Ariz.

Application April 22, 1947, Serial No. 743,167

3 Claims. (Cl. 98—40)

1 This invention relates to heat transfer apparatus of the type employed for space heating or space cooling and is particularly directed to an improved form of air deflector or louver employed in connection with such apparatus.

The principal object of this invention is to provide an improved form of louver for deflecting air issuing from a space heater or space cooler.

Another object is to provide a compound curve louver which acts to spread a current of air laterally as well as to deflect it downwardly.

A more particular object is to provide a louver having substantially a straight horizontal leading edge and a curved trailing edge, the trailing edge being curved about a large radius in horizontal plane and being curved about a small radius in vertical section.

A further object is to provide a louver of this type which may be stamped from a single sheet of metal.

Other objects and advantages will appear hereinafter.

In the drawings:

Figure 1 is a top plan view of the preferred embodiment of my invention.

Figure 2 is a rear elevation thereof.

Figure 3 is a sectional elevation taken substantially on the lines 3—3 as shown in Figure 1.

Figure 4 is a perspective view showing the leading edge of the preferred form of louver.

Figure 5 is a plan view partly broken away showing installation of a louver embodying my invention in a space heater.

Figure 6 is a perspective view of the heater shown in Figure 5 illustrating a plurality of louvers in operating position.

Referring to the drawings, the louver generally designated 10 may be employed in connection with deflecting any stream of air and finds particular usefulness in connection with space heaters and space coolers.

While I have illustrated the preferred form of louver in connection with a space heater, it is to be understood that it is also used with space coolers of every type.

As illustrated in the drawings, the louver may be formed of any suitable material, such as metal, and extends laterally between side stiffeners 12 and 13. A straight horizontal leading edge 14 is joined integrally with the side stiffeners 12 and 13 and the trailing edge 15 is curved in horizontal plane and in vertical section and also is joined integrally with the side stiffeners 12 and 13.

2 The surface 16 of the louver between the leading edge 14 and the trailing edge 15 is curved about a relatively large radius R_1 as shown in Figure 3. The trailing edge 15 is curved in vertical section along the relatively small radius R_2 as shown in Figure 3. The trailing edge 15 is also curved about a relatively large radius R_3 in horizontal plane as shown in Figure 1. In other words, the trailing edge 15 is shaped with a double radius in the form of a compound curve.

The louvers 10 may be installed on the space heater 11 in any suitable or convenient manner. As shown in the drawings, the side stiffeners 12 and 13 may be positioned adjacent the side walls 17 and 18 and maintained in position by means of clips 19 and fastening elements 20, which elements extend through openings 27.

The louvers 10 extend horizontally across the opening 21 through which warm air is directed outwardly by means of a fan (not shown). The air stream issues between the heat fins 22 which extend vertically in parallel relation within the body of the heater 11. The air stream issuing from the opening 21 is broken up and deflected by means of the louvers 10 to spread the air laterally and deflect it downwardly and thus contribute to the uniform space heating. The arrows 23 illustrate the action of the louvers 10 in deflecting the stream of air issuing from the central opening 21.

The heater 11 may be of any suitable or desirable type and as illustrated, is adapted to be suspended above the floor level by means of the terminal fittings 24 and 25. An outlet 26 may be provided for connection to a stack (not shown) to carry off fumes.

Having fully described my invention, it is to be understood that I do not wish to be limited to the details herein set forth, but my invention is of the full scope of the appended claims.

I claim:

1. A compound curved louver for deflecting a current of air, comprising a curved sheet of material provided with downwardly extending side stiffeners integrally formed therewith, the sheet having a substantially straight horizontal leading edge and a curved trailing edge, the sheet curving gradually from the leading edge to the trailing edge, the trailing edge being convexly curved in plan and curved away from the horizontal, whereby an air stream directed normal to the leading edge is spread laterally and deflected at an angle.

2. In a compound curved louver for deflecting a current of air issuing from heat transfer ap-

paratus, a curved sheet of material provided with downwardly extending side stiffeners integrally formed therewith, the sheet having a substantially straight horizontal leading edge extending between the side stiffeners, the trailing edge of the sheet being convexly and symmetrically curved in plan and curved downwardly away from the horizontal and terminating in a horizontal plane, whereby an air stream may be spread laterally and deflected downwardly.

3. A compound curved louver for deflecting a current of air, comprising a curved sheet of material provided with downwardly extending side stiffeners integrally formed therewith, the sheet having a substantially straight horizontal leading edge and a curved trailing edge, the sheet curving about a relatively large radius from the leading edge to the trailing edge, the trailing edge being convexly and symmetrically curved in plan and being curved about a relatively small 20

radius away from the horizontal and terminating in a horizontal plane, whereby an air stream directed normal to the leading edge is spread laterally and deflected at an angle.

OSCAR C. PALMER.
